UNITED STATES PATENT OFFICE.

JOSEPH WIESER, OF NEW YORK, N. Y.

PNEUMATIC VALVE-ACTION FOR PLAYER-PIANOS.

No. 895,220.

Specification of Letters Patent.

Patented Aug. 4, 1908.

Application filed February 1, 1908. Serial No. 413,844.

To all whom it may concern:

Be it known that I, JOSEPH WIESER, a citizen of the United States, residing in New York, in the borough of Brooklyn, county of 5 Kings, and State of New York, have invented certain new and useful Improvements in Pneumatic Valve-Actions for Player-Pianos, of which the following is a specification.

This invention relates to an improved 10 pneumatic valve-action for player-pianos which is located above the rear-ends of the key-levers in the space between the front-panel of the upright piano-case and the piano-actions in such a manner that the 15 piano-actions are actuated, not by the key-levers, but by lifters connected with the hammer-jack supporting levers, the actions being arranged in tiers vertically one above the other and the motion of the actuating 20 bellows transmitted by intermediate lever-mechanisms to the lifters; and for this purpose the invention consists in the novel features of construction which will be fully described hereinafter and finally pointed out in 25 the claims.

In the accompanying drawings, Figure 1 represents a vertical transverse section of my improved pneumatic valve-actions for player-pianos, taken on line 1, 1, Fig. 2, and Fig. 2 is 30 a front-elevation of a number of pneumatic valve-actionsshowing the transmitting mechanisms operated by the same, the valve-actions being arranged in tiers vertically one above the other in front of the piano-actions.

Similar letters of reference indicate corresponding parts.

Referring to the drawings, *a* *a*¹ represent two transverse rails which are located above the rear-ends of the key-levers in the space 40 between the upper front-wall of an upright piano-case and the piano-actions, the rail *a* being made of angular shape, while the rail *a*¹ is made of oblong shape, both being supported in a suitable manner on the frame of 45 the upright piano. On the upper transverse rail *a* are supported two tiers of pneumatic valve-actions *b* *b*¹, while on the lower rail *a*¹ are likewise supported two tiers of valve-actions *b* *b*¹, the lower group of tiers being 50 slightly set back relatively to the upper group of tiers so as to provide the required space for the motion-transmitting mechanisms. Each tier is composed of a certain number of individual pneumatic valve-actions of the construction shown in the application for Letters Patent of the United States, filed by me

on July 27, 1907, Serial No. 385,888, and officially allowed on September 23, 1907. In the space between the upper and lower groups of tiers of valve-actions *b* *b*¹ is arranged a third transverse rail *a*², which serves for supporting as many elbow-levers *d* as there are valve-actions in the upper and lower tiers, which elbow-levers are fulcrumed to the rail *a*² and connected at their upper ends by pivot-links *d*¹ provided with adjustable buttons *d*² with the projecting toes *d*³ on the movable members of the bellows *e* actuated by the valve-actions in the upper and lower groups of tiers. The lower arm of each elbow-lever *d* is connected by a vertical wire *f*¹, provided with adjustable buttons *f*² at its upper and lower threaded ends, with the front-end of a lever *f* which is fulcrumed to a lug *f*³ attached to the lower rail *a*¹. The opposite or rear-end of the lever *f* is connected by a lifter-rod *g* provided with a threaded lower end and an adjustable button *g*¹ on said end, and with a fixed button *g*² at the upper end, with the supporting lever *h* of a corresponding piano-action, said lever being fulcrumed to the upper end of the abstract *u* in the usual manner.

The hammer-jack, damper and other parts of the piano-action are supported on the lever *h* in the usual manner, the upper lifter-button *g*² acting on the felt-cushioned front-portion of the lever *h*, as shown clearly in Fig. 1. On the lower threaded part of the lifter-rod *g* is arranged a weight *g*³ by which the operative parts described, viz., the elbow-lever *d*, connecting rod or wire *f*¹, fulcrumed transmitting lever *f* and lifter-rod *g*, are returned into normal position as soon as the pneumatic valve-action has been operated. The lifter- 55 rods *g* are guided in guide-openings of a fourth transverse rail *a*³, the front-part of which is provided with a felt-cushion for the movable members of the bellows of the lower tiers of valve-actions, while a fifth rail *a*⁴, which is also provided with a front-cushion, serves for arresting the movable members of the bellows of the upper tiers of valve-actions. In front of each elbow-lever *d* is arranged in the lower part of the rail *a* an adjustable stop-cushion *d*⁴, the shank *d*⁵ of which passes through the lower part of the rail *a* into the recessed front-portion of the same, so that the heads of the shanks can be adjusted from the front of the piano on removing the front-panel, and thereby the oscillating movement or throw of the elbow-levers *d* under the in-

fluence of the pneumatic valve-actions and the vertical motion of the lifter-rods connected with the elbow-levers can be accurately and effectively controlled.

- 5 Each valve-action is connected by a small rubber-tube i with the corresponding channel of the tracker which is supported at a suitable point in the case above the upper tiers of valve-actions. The rubber-tubes of 10 the upper tiers of valve-actions, as well as the rubber-tubes of the lower tiers of valve-actions, are located in parallel grooves in the front-walls of the upper tier of valve-actions so as to keep them in proper position. The lower ends of the rubber-tubes i are connected by curved channels i^1 with the valve-actions of the upper tiers and by curved tubes i^2 with the valve-actions of the lower tiers, as shown in Fig. 1. As soon 15 as an opening in the perforated music-sheet passes over the inlet-opening of the tracker-channel, the corresponding valve-action is operated in the usual manner, the bellows which is connected therewith being collapsed, and thereby the intermediate motion-transmitting lever-mechanism and the lifter-rod actuated and the corresponding piano-action operated and the string sounded by the blow of the hammer. As soon as the 20 inlet-opening in the tracker is closed, the valve-action is returned to its normal position, the bellows expanded and the motion-transmitting lever-mechanism and lifter-rod returned to their normal position of rest, 25 ready for the next action.

For preventing any interference of the bellows and their closely-arranged motion-transmitting lever-mechanisms, the stationary members of the bellows of the upper tiers of 30 valve-actions are arranged sidewise of each other and connected with their valve-actions by openings o o^1 respectively in the upper and middle portions of the stationary members of the bellows, while the bellows of the 35 lower tiers of valve-actions are also provided with connecting openings o^2 o^3 in the stationary members at their middle and lower portions, the bellows being arranged in staggered relation, that is to say, having 40 their transverse center planes out of vertical alignment with those of the bellows in the opposite row. In order that this arrangement of the bellows may be effected, it is necessary that the valve-actions of the lower 45 tiers be arranged in staggered relation with respect to those of the upper tiers, as shown.

The motion-transmitting lever-mechanisms are located equidistantly alongside of each other in such a manner that they do not 50 interfere with each other when the bellows are collapsed by the suction-action of the power-bellows on their valve-actions when a hole in the music-sheet passes over the tracker-channel. In this manner the action 55 of the bellows and the motion-transmitting

lever-mechanisms for the piano-actions can be all arranged in the space above the key-levers. The wind-chests of the valve-actions are connected at the ends of the upper and lower tiers by vertical channels with the power-bellows operated by the pedals. The entire pneumatic valve-mechanism is capable of removal for repairs on removing the front-panel of the upper part of the piano-case.

Having thus described my invention, I claim as new and desire to secure by Letters Patent:

1. The combination, with upper and lower groups of pneumatic valve-actions arranged in tiers, of bellows connected therewith and controlled thereby, and lifting mechanism comprising levers mounted between the two groups of valve-actions and to which bellows of both groups are connected, and lifting rods operated by said levers.

2. The combination, with upper and lower groups of pneumatic valve-actions arranged in tiers, of bellows arranged at the rear of said valve-actions and also divided into upper and lower groups, fulcrumed levers arranged between the groups of valve-actions and to which bellows of both groups are alternately connected, and lifting mechanism operated from said levers.

3. The combination, with upper and lower groups of pneumatic valve-actions arranged in tiers, of upper and lower groups of bellows arranged at the rear of said valve-actions, the bellows of one group being staggered with respect to the other group, a plurality of fulcrumed levers in the space between the valve-actions and to which the bellows of said groups are alternately connected, and lifting mechanism operated from said levers.

4. The combination, with upper and lower groups of valve-actions arranged in tiers, and bellows connected with said valve-actions, of a rail between the two groups of valve-actions, a plurality of levers fulcrumed on said rail, and lifting mechanism operated by said levers.

5. The combination, with upper and lower groups of valve-actions, and upper and lower groups of bellows connected therewith at the rear thereof, of lifting mechanism comprising rods operated by both groups of bellows and arranged below the upper group and at the rear of the lower group.

6. The combination, with upper and lower groups of valve-actions, and upper and lower groups of bellows connected therewith at the rear thereof, of lifting mechanism operated by both groups of bellows and comprising connections extending downwardly in front of the lower group of valve-actions and upwardly at the rear of said group.

7. The combination, with upper and lower groups of valve-actions, of upper and lower groups of bellows connected therewith at the

5 rear of the same, hammer-jack supporting levers at the rear of the bellows, levers connected with the bellows of both groups and arranged in the space between the groups of 10 valve-actions, and lifting rods operated from said levers and abutting at their upper ends against said hammer-jack supporting levers.

8. The combination, with a pneumatic valve-action and a bellows operated thereby, 10 of a fulcrumed lever mounted above the valve-action, a connecting rod or wire connected with said lever and extending downwardly in front of the valve-action, a lifting rod at the rear of the valve-action, an operative connection between said lifting rod and 15 said connecting rod below the valve-action, and a piano-action operated by said lifting rod.

9. The combination, with upper and lower groups of valve-actions, of bellows connected 20 with said valve-actions at the rear thereof, lifting rods arranged at the rear of the bellows of the lower group of valve-actions, and connections between said lifting rods and said bellows comprising connecting rods at 25 the front of the lower group of valve-actions, and levers pivoted below said lower group of valve-actions and upon which said connecting rods and said lifting rods rest.

In testimony, that I claim the foregoing as 30 my invention, I have signed my name in presence of two subscribing witnesses.

JOSEPH WIESER.
